[57] CLAIM

The ornamental design for a bottle, as shown and described.

DESCRIPTION

FIG. 1 is a perspective view of a bottle, embodying our new design;

FIG. 2 is a front elevational view thereof;

FIG. 3 is a top view thereof;

FIG. 4 is a bottom view thereof;

FIG. 5 is a back elevational view thereof;

FIG. 6 is a first side elevational view thereof; and,

FIG. 7 is a second side elevational view thereof.

The broken lines shown in the figures are for illustrative purposes only, and form no part of the claimed invention.
